UNITED STATES PATENT OFFICE.

FRANK D. DIBBLE, OF MINNEAPOLIS, MINNESOTA, ASSIGNOR, BY DIRECT AND MESNE ASSIGNMENTS, TO THE AMERICAN ACETYLENE GAS COMPANY, OF SAME PLACE.

ACETYLENE-GAS GENERATOR.

SPECIFICATION forming part of Letters Patent No. 596,103, dated December 28, 1897.

Application filed July 10, 1896. Serial No. 598,711. (No model.)

To all whom it may concern.

Be it known that I, FRANK D. DIBBLE, a citizen of the United States, residing at Minneapolis, in the county of Hennepin and State 5 of Minnesota, have invented certain new and useful Improvements in Acetylene-Gas Generators; and I do hereby declare the following to be a full, clear, and exact description of the invention, such as will enable others 10 skilled in the art to which it appertains to make and use the same.

My invention has for its object to provide certain improvements in that class of gas apparatus which are used either as generators 15 or holders and which involve a pair of telescoping sections, one of which is water-seated and mounted for movement within the other. This class of apparatus is now in general use for the purposes of generating or holding or 20 generating and holding acetylene gas. It may here be stated that in practice these devices, when used to control the production of acetylene gas by the contact of water and calcic carbid, have been found seriously defective in that the movable telescopic part is 25 liable to be thrown out of working position by very rapid overproductions of gas. This overgeneration of gas is usually due to the fact that the calcic-carbid bodies become too 30 deeply submerged, so that they carry an excessive amount of water with them when they are removed from contact with the main body of the water, thus continuing the generation of gas after a time when it should have been 35 stopped. When the movable section of the tank is thus thrown out of working position, the gases will of course escape into the room in which the apparatus is located, and fires, explosions, and many other damages will naturally follow.

To obviate the above dangers and render the apparatus more safe is the object of my invention.

To these ends my invention comprises the 45 novel devices and combinations of devices hereinafter described, and defined in the claims.

The preferred form of my invention, as well as a modification thereof, is illustrated in the

accompanying drawings, wherein like letters 50 refer to like parts throughout both views.

Figure 1 is a view, principally in side elevation but with some parts broken away and others shown in section, illustrating the preferred form of my invention; and Fig. 2 illustrates a modification thereof.

Referring to Fig. 1, *a* indicates the fixed tank-section, provided with a flanged false bottom *a'* and a draw-off cock or faucet *a''* at the central portion of its conical bottom, and 60 *a³* indicates the inverted cup-like tank-section, which is mounted for vertical telescopic movement within the fixed tank-section *a*, and is water-seated by means of a column of water *z*, contained in said tank *a*. The movable tank-section *a³* is provided with a carbid-holder *a⁴*, of any ordinary form, which is adapted to be moved into and out of contact with the column of water *z* by the movement of said tank *a³*. The device just described 70 is, in this particular case, the generator.

In connection with the generator just described I have also shown a storage-tank or gas-holder, which also comprises a pair of water-seated telescopic sections, of which *b* 75 indicates the fixed member and *b'* the vertically-movable member of the same. The fixed section *a* of the generator and the fixed section *b* of the holder or storage-tank are in communication through a valved gas-conveying pipe *b²*. This gas-conveying pipe *b²* extends upward, with one end above the level 80 of the column of water contained in the storage-gasometer *b* and with its other end above the column of water contained in the 85 generator. The arrangement of this pipe connection is of the most ordinary construction and for the purposes of this case is not thought to need further illustration.

The extreme upward movement of the movable section *a³* of the generator is limited by means of chains *a⁵*, (as shown, four in number,) which are rigidly secured at their upper ends to said movable section *a³* and at their lower ends to eyes *a⁶* on the upper edge 95 of the fixed tank-section *a*. If desired, the lower ends of these chains *a⁵* may be removably secured to the eyes *a⁶* by means of snap-

hooks a^7 . The chains a^5 are of such length that they will permit the movable tank-section a^3 to move upward nearly but not quite out of the column of water z .

5 The fixed tank-section a of the generator is provided near its upper end at a point above the column of water z with escape-passages a^8 , (as shown, four in number.) As shown, the extreme upper edge of the tank a is flanged 10 or turned inward at a^9 to form a close but loose joint with the periphery of the tank-section a^8 . From each of the escape-passages a^8 escape or overflow pipes a^{10} extend downward against the sides of the tank a and terminate in converging nozzle ends a^{11} , which project inward through the flanged false bottom a' , so that they are all adapted to discharge the overflow of water which passes therethrough into a common vessel—such, for 15 example, as the catch basin or box c , located beneath the same. The upward movement of the movable section b' is limited by chains b^3 , which are secured at their upper ends to the section b' and at the lower ends to section b .

20 As shown, both the generator and holder or storage-tank are supported by a bench or table g , which is cut away, as shown at g' , to permit the discharge from the overflow-pipes 25 $a^{10} a^{11}$ and from the faucet a^2 into the catch basin or box c .

25 The operation of my improvements will be substantially as follows: The ordinary generating action of the generator is a matter of such general knowledge that further comment thereupon is not deemed necessary. If, however, a too rapid or sudden production of the gas therein contained should take place, the movable tank-section a will of course be 30 thrown upward to the limit permitted by the chains a^5 . The gases then, instead of being permitted to rise, will force the water z contained in the tank-section a downward, which will of course cause the same to rise in the 35 narrow circular compartment formed between the sections a and a^3 until it reaches the altitude of the escape-passages a^8 , where it will find a ready overflow through the overflow-pipes $a^{10} a^{11}$, through which it will be 40 charged into the catch-basin c . By this means 45 the gas will be held in the generator while the water will be blown out thereby. It must

be evident that this safety device will render practically impossible any serious accident from an explosion of the gases in the generator or holder. Obviously the fixed section b of the storage tank or holder might also be provided with similar overflow-pipes, but I have not deemed it necessary to illustrate this feature in the drawings.

55 60 In the modification illustrated in Fig. 2, f indicates the fixed section of the gas apparatus and f' the telescopically-movable section of the same. In this modification the fixed tank-section f is provided with perforated 65 brackets f^2 , and the movable section f' is likewise provided with perforated brackets f^3 . The upward movement of the movable tank-section f' is limited by means of bolts f^4 , which work through the coöperating pairs of 70 brackets $f^2 f^3$ and are provided with headed ends f^5 .

75 What I claim, and desire to secure by Letters Patent of the United States, is as follows:

1. The combination with the fixed and exterior member of a pair of gasometer-sections, of one or more overflow tubes or passages opening from the upper portion thereof, at a point or points above the normal altitudes of the sealing liquid therein contained, the telescopically-movable gasometer-section, liquid-seated within said fixed section, and a stop device for limiting the upward movement of said movable gasometer-section, whereby overgenerations of gas will first cause said 80 movable tank-section to rise to its limit and will then cause the overflow or escape of the sealing liquid through said overflow tubes or 85 passages, substantially as described.

2. The combination with the tank-section a , provided with the overflow-passages a^8 at its upper end, of the overflow-pipes a^{10} leading from said passages a^8 and terminating in the converging nozzle-sections a^{11} , the movable tank-section a^3 , and the flexible connections 95 a^5 secured at their upper ends to said tank-section a^3 and at their lower ends to said tank-section a , substantially as described.

90 In testimony whereof I affix my signature in presence of two witnesses.

FRANK D. DIBBLE.
